UNITED STATES PATENT OFFICE.

JAMES NATHAN GLOVER, OF KANSAS CITY, KANSAS.

AIR CONTROL FOR LOCOMOTIVE FIRE BOXES.

Application filed October 22, 1925. Serial No. 64,231.

My present invention relates generally to locomotive fire boxes, and more particularly to the control of air passing into the same, my primary object being the provision of means adjacent to the air inlet opening, which will displace the usual laterally swinging fire door and which will function to direct the strong current of air that passes inwardly through the fire door opening, down wardly onto the fire in order to insure that such air current strikes the fire several feet inwardly beyond the fire door opening and spreads over the fire, meeting the heat flare coming from beneath the arch and bringing about the desired chemical action for perfect combustion so that the black smoke will be consumed as a result thereof.

A further object of my invention is the provision of an air controlled apparatus which will function to keep the cold air close to the fire and away from the flue and crown sheets, bringing about a higher degree of superheat and less back pressure than is usually the case, and which will in addition, function as a baffle to protect the fireman from the excessive heat of the fire box.

In the accompanying drawing which illustrates my present invention and forms a part of this specification:—

Figure 1 is a front elevation showing a locomotive firebox equipped with my invention applied.

Figure 2 is a side view thereof,

Figure 3 is a detail perspective view of certain portions of the connections proposed by my invention, and

Figure 4 is a detail vertical section partially through the baffle plate or deflector.

Referring now to these figures, and particularly to Figures 1 and 2, I have shown a locomotive fire box in a general way at 10, having the usual framed fire door opening 11 for the entrance of air into the fire box. Ordinarily the frame 12 around the opening 11 supports a laterally swinging door which is displaced in accordance with my invention in favor of a vertically swinging baffle member or deflector plate 13, secured along its upper edge in connection with a rod 14.

This rod extends across the upper portion of the opening 11 and is turnable in bearing members 15 secured to the frame 12, whereby the baffle member or deflector plate 13 is swingable vertically. The rod 14 is extended at one side of the frame 12 and is provided with a threaded angular stem 16 on

which weights 17 may be disposed so as to counterbalance the deflector plate and render it an easy matter to adjust the same as well as to hold it in adjusted position, and especially in its normal position in which it inclines inwardly and downwardly at an angle of approximately forty-five degrees (45°) as shown in Figure 1 so as to deflect the incoming air current downwardly onto the fire in the fire box as shown by the arrows in Figure 2.

In order that the baffle member or deflector plate 13 may be raised to the fully open position, a treadle bar 18 is hinged to the outside of the fire box below and at one side of the opening 11 and connected by a cable or other suitable connection 19 to a lever 20, the connection 19 being joined to this lever at a point intermediate the ends of the latter as will be seen by reference to Figures 1 and 3.

At one end, the lever 20 is pivotally mounted at 21 below the oil pan 22 and at its opposite end said lever is connected by a series of hinged links 23 with a lug 24 outstanding forwardly from the upper central portion of the baffle member or deflector plate 13 so that the connecting members 23 thus accommodate themselves to the swinging movements of the lever 20 as well as the baffle member or deflector plate 13.

The lever 20 is also provided near its free end with an upstanding stop lug 25, and the parts are so arranged that this stop lug comes into engagement with the lower surface of the oil pan 22 when the baffle member or deflector plate 13 is in its normal angular position above described.

Obviously, depression of the treadle bar 18 forces the free end of the lever 20 downwardly and, through the connections between this lever and the baffle member or deflector plate 13, the latter is caused to swing inwardly and upwardly to its full open position. Immediately upon release of the treadle bar, however, the baffle member or deflector plate 13 drops back to its normal position, as described.

As shown in Figure 4, it is preferable that the baffle member or deflector plate 13 be formed of two sections 26 and 27 having between them a layer of asbestos and the like 28, due to which construction and the fact that the relatively cool air entering the fire box strikes the baffle member or deflector plate, enables the same to successfully with-

stand the intense heat of the fire box for a considerable period without burning or warping.

I claim:—

1. In a locomotive fire box having an air feed opening and a projecting support above said opening, a baffle member hinged along its upper edge within the upper portion of said opening and having an angular outstanding lug intermediate its ends, a lever pivoted at one end to a portion of the said support and having a flexible connection depending from its opposite end and between the same and the said baffle lug including a series of hinged links, a treadle bar, and a flexible connection between the treadle bar and said lever engaging the latter intermediate its ends.
- 10 2. In a locomotive fire box having an air

feed opening and a projecting support 20 above said opening, a baffle member hinged along its upper edge within the upper portion of said opening and having an angular outstanding lug intermediate its ends, a lever pivoted at one end to a portion of the 25 said support and having a flexible connection depending from its opposite end and between the same and the said baffle lug including a series of hinged links, a treadle bar, and a flexible connection between the 30 treadle bar and said lever engaging the latter intermediate its ends, said lever having an upper angular extension at its free end engageable with the said support to limit and prevent complete closing of the 35 fire box opening.

JAMES NATHAN GLOVER.
